UNITED STATES PATENT OFFICE.

GUNDER P. SMAAGAARD, OF CERROGORDO, MINNESOTA.

NECK-YOKE.

1,106,417.

Specification of Letters Patent. Patented Aug. 11, 1914.

Application filed April 29, 1914. Serial No. 835,185.

To all whom it may concern:

Be it known that I, GUNDER P. SMAAGAARD, a citizen of the United States, residing at Cerrogordo, in the county of Lac qui Parle 5 and State of Minnesota, have invented certain new and useful Improvements in Neck-Yokes; and I do hereby declare the following to be a full, clear, and exact description of the invention, such as will enable others skilled in the art to which it appertains to 10 make and use the same.

My invention has for its object to provide an improved neck yoke, and, to this end, it consists of the novel devices and combinations of devices hereinafter described and defined in the claims.

In the accompanying drawings, which illustrate the invention, like characters indicate like parts throughout the several 20 views.

Referring to the drawings, Figure 1 is a rear elevation of the improved neck yoke, some parts being broken away, and some of the exposed parts being shown in section; 25 Fig. 2 is a plan view of the neck yoke and the forward end portion of a vehicle pole, some parts being indicated in different positions by means of dotted lines, and some parts being broken away; and Fig. 3 is a 30 view showing the vehicle pole in side elevation and the improved neck yoke applied thereto, in transverse section.

The numeral 1 indicates a vehicle pole having the customary metallic pole cap 2, 35 with a stop lug 3.

Referring now to the improved neck yoke, the numeral 4 indicates a pair of axially alined tubes, spaced apart, at their inner ends. As shown, these tubes 4 are formed 40 from sheet metal, with their longitudinal edges turned outward, to afford depending flanges which are secured together by rivets; or, if desired, these longitudinal edges may be welded. Telescoped into the outer 45 end of each tube 4 is a reinforcing sleeve 5. Collar strap loops 6 are secured, one to each 50 end of the neck yoke. These loops, as shown are in the form of U-shaped bolts, with their prongs passed transversely through the tubes 4 and sleeves 5, and are secured in position by nuts having screw-threaded engagement therewith.

Interposed between the spaced inner ends of the tubes 4 is a pole socket 7, having, at 55 its forward end, a head or laterally projecting annular flange 8, and having, at its other

end, upper and lower segmental lugs 9. The inner end portions of the tubes 4 are connected by upper and lower channel straps 10, rigidly secured thereto, as shown, by 60 nut-equipped bolts. These straps 10, at their intermediate portions, are outwardly and transversely bulged, at 12, to receive and hold therebetween the pole socket 7. The head 8 of the pole socket 7 works on segmental surfaces 13 formed on the outer longitudinal edges of the straps 10, and the segmental lugs 9 work in segmental notches 14 formed in the rear longitudinal edges of 65 said straps. The straps 10, at the segmental notches 14, are, as shown, preferably expanded, to afford relatively wide wearing surfaces, on which the lugs 9 work. Obviously, the head 8 and lugs 9 prevent endwise removal of the pole socket from the 70 neck yoke, but permit a limited swinging movement of the pole socket longitudinally of the neck yoke. These elements also permit a limited rotary movement of the pole 75 socket, with respect to the neck yoke.

Integrally formed with the lower lug 9 is a clip 15, adapted to interlock with the lug 3 on the pole cap 2, by substantially a quarter turn of the neck yoke in respect to the pole. This clip, when interlocked with the lug 3, holds the neck yoke against longitudinal sliding movement on the pole cap 2, but permits a free rotary movement in respect thereto.

What I claim is:

1. A neck yoke comprising a pair of axially alined tubes, a pole socket having at its rear end portion segmental lugs, said pole socket being interposed between the inner ends of said tubes, and upper and lower channel straps connecting said tubes and embracing said pole socket, said straps having in their inner longitudinal edges segmental notches in which said lugs work.

2. A neck yoke comprising a pair of axially alined tubes, a pole socket, having at its forward end a head, and having at its other end upper and lower segmental lugs, said pole socket being interposed between the inner ends of said tubes, and upper and lower channel straps embracing and rigidly secured to the inner end portions of said tubes, said straps being transversely bulged outward to receive said pole socket between its head and segmental lugs, to hold the 100 same against removal from said straps, said straps having in their inner longitudinal 105

edges segmental notches in which the segmental lugs of said pole socket work.

3. A neck yoke comprising a pair of axially alined body members, a pole socket having, at its rear end portion, segmental lugs, said pole socket being interposed between the inner ends of said body members, and upper and lower straps connecting said body members, and embracing said pole

socket, said straps having, at their inner 10 longitudinal edges, segmental notches, in which said lugs work.

In testimony whereof I affix my signature in presence of two witnesses.

GUNDER P. SMAAGAARD.

Witnesses:

P. P. SMAAGAARD,
BERNICE P. SMOGARD.
